UNITED STATES PATENT OFFICE.

JACOB SARDO, OF JOHNSTOWN, PENNSYLVANIA.

CLOTHESLINE REEL.

1,352,994.

Specification of Letters Patent. Patented Sept. 14, 1920.

Application filed February 14, 1920. Serial No. 358,694.

To all whom it may concern:

Be it known that I, JACOB SARDO, a citizen of the United States, residing at Johnstown, in the county of Cambria and State 5 of Pennsylvania, have invented certain new and useful Improvements in Clothesline-Reels, of which the following is a specification.

My invention relates to clothes line reels, 10 and especially to that class of reels employed for supporting a clothes line in an elevated position where the clothes have to be reeled out on the line from a given point (usually one end of the line) when they 15 are put out for drying, and then reeled back again to the same point when they are dry and ready to be taken off the line.

The object is to provide a reel which will easily retain the line thereon without undue 20 tension on the line, and one which will permit variations in the tension of the line, working well whether the line be taut or slack.

A leading feature of the invention consists of a plurality of hooks having comparatively long shanks loosely pivoted at 25 their upper ends around the periphery of a vertical drum, around which shanks the clothes line is received upon the drum between the upper and lower ends of said 30 hooks.

The invention consists in certain novel features of construction and arrangement of parts as will be hereinafter described 35 and claimed, reference being had to the accompanying drawings forming a part hereof, and in which:—

Figure 1 is a view illustrating my device in use.

Fig. 2 is a side elevation showing the clothes line in operative position on the device.

Fig. 3 is a view partly in section, showing the method of securing the axle of the 45 drum to the frame upon which it is supported; and,

Fig. 4 is a view showing the device in side elevation without the line.

Referring further to the drawings by 50 numerals, the supporting frame of the device consists of a vertical bar 1, and a horizontal bar 2, securely held approximately at right angles to each other by a brace 3.

A drum 4 is supported in a vertical position 55 on an axle 5, which is provided with a reduced upper end 5^a extending up

through the horizontal bar 2 and the end 3^a of the brace 3. The reduced upper end 5^a of the axle is threaded to receive thereupon a nut 6. A shoulder 7 is formed at 60 the junction of the reduced portion 5^a with the main portion of the axle; and the horizontal bar 2 and the end 3^a of the brace are clamped in rigid engagement with each other between said shoulder and the nut 6. 65 This arrangement also serves to hold the axle 5 rigid on the frame of the device.

The drum 4 is provided with annular flanges 8 and 9, at its upper and lower ends respectively. The axle 5 is provided at its 70 lower end with a reduced portion 5^b upon which is received a washer 10 held in position by a pin 11 which passes through a suitable opening in said reduced portion, and this washer 10 supports the drum 4 on the 75 axle 5.

Attention is now called to a very important feature of my device, namely, the hooks 12 which are loosely pivoted at their upper ends around the periphery of the drum 4 80 near the upper end of said drum, and are preferably spaced equidistant from each other. These hooks naturally tend to hang in a vertical position by gravity with their lower curved ends 12^a slightly above the 85 lower flange 9 of the drum.

The clothes line passes like a belt or endless carrier around that portion of the drum which is occupied by the hooks 12, so that the hooks are between the line and the drum 90 and thereby partially prevent the line from coming into direct frictional engagement with the surface of the drum.

Any desired number of these hooks may be employed.

In the operation of the device, two of the drums 4 are usually employed—one at each end of the line or endless carrier. (Of course, more than two drums can be employed if desired, since the line surrounds 100 them like a belt.)

The frame of the device is secured to the wall or other support therefor by means of bolts or screws 13 (Fig. 2) which pass through the vertical bar 1 of the frame into 105 the wall. The clothes line 14 extends like a belt from one drum to the other, and as the clothes are placed, piece by piece, on the line and secured in the usual manner, the vacant portion of the line is successively drawn up step by step by a pull thereupon by the hand of the operator. As the

hooks 12 are in frictional engagement with the line, the pull upon the line will cause the lower free ends of the hooks to swing in the direction of the pull especially at 5 the sides of the drum as they successively face at right angles to the longitudinal extent of the line. And as the hooks swing in this direction (as illustrated in Fig. 2) their outwardly curved lower ends which 10 are necessarily in engagement with the line or the clothes thereupon, move upwardly a certain distance, and thus lift the line on the drum to that extent and keep it from moving down into engagement with the 15 flange 9 at the lower end of the drum. Of course, if the line be very tight, the flange 9 would keep it on the drum anyhow, but by the employment of the hooks 12, the line is easily kept on the drum without 20 being very tight, which is a matter of great advantage, since the line has to be reeled around these drums not only in putting the clothes on the line when the line necessarily becomes wet, but also when the clothes are 25 taken off the line when the line is dry and somewhat lengthened out from what it was when it was wet. That is to say;—The nature of the service required of the line is such that it unavoidably causes the line 30 to vary in length at different times; so that if when it is dry it is made tight enough to hold it safely on the drums by means of the flanges 9, it will be too tight when the line is made wet and draws up or contracts 35 in length, so that it will in that case impose undue strain upon the line, and upon the entire device, and thereby sometimes causes the line to break when the weight of a washing of wet clothes is imposed thereupon in 40 addition to the strain imposed by the contraction of the line.

It should also be taken into consideration that in lines of this class upon which the clothes are reeled in and out, the lines often 45 extend across a yard from a point adjacent a second-story window—*i. e.*, comparatively high up from the ground—so that a break in the line causes unusual trouble, because the coöperating drum at the opposite side 50 of the yard from the window, may be secured to a pole or to the wall of a shed, or may otherwise be comparatively inaccessible,

so that replacing the line on the drums after a break is apt to be attended with considerable inconvenience.

Hence the decided advantage of my device becomes apparent, since it permits the line to come and go, so to speak, and works well when the line is comparatively slack, and never requires that undue tension be 60 imposed upon the line.

When the hooks 12 of a drum successively move around into position facing the other drum, the lower curved ends of the hooks move out of engagement with the line or 65 the clothes thereupon and swing down by gravity to their lowest position ready to presently reengage the line and slightly lift the same on the drum again as before.

If four or more of the hooks 12 are employed, there will always be at least two of the hooks on approximately opposite sides of the drum in lifting engagement with the line.

Fig. 4 shows the normal position which 75 the hooks always tend to assume when left free from the influence of the line; and, Fig. 3 as described shows how the axle 5 is held as rigid on the frame as if it were integral therewith.

Inasmuch as the hooks 12 hold the clothes line spaced from the drum, the clothes pins in passing around the drum will usually come between the hooks and thus pass around the drum much more easily than if 85 only plain drums with broad bottom flanges were used. This feature is here referred to because with my device the clothes are intended to be reeled around the drums so as to hang from both sides of the line.

Having now described my invention, what I claim as new and desire to secure by Letters Patent is;—

In a device of the character described, the combination with a vertical rotatable 95 drum, of a plurality of hooks pivoted at their upper ends to the periphery of said drum and adapted to normally extend downwardly by gravity from their respective pivots in parallelism with each other, and 100 having their lower ends free and turned outwardly.

In testimony whereof I affix my signature.
JACOB SARDO.
